INVENTOR
Victor Sence
BY *J. H. Russek*
ATTORNEY

UNITED STATES PATENT OFFICE.

VICTOR SENCE, OF NEW YORK, N. Y.

ELECTRIC DUMB-BELL.

Application filed May 15, 1925. Serial No. 30,510.

To all whom it may concern:

Be it known that I, VICTOR SENCE, a citizen of the United States of America, residing at New York city, borough of Manhattan, county and State of New York, have invented certain new and useful Improvements in Electric Dumb-Bells, of which the following is a specification.

My invention relates to exercising apparatus which is capable of generating an electric current which will pass through the body of the user so that he will get the combined beneficial result of the physical exercise and of the stimulation resulting from the passage of the current. To this end it comprises a pair of objects such as a pair of dumb-bells which can be grasped one in each hand by the user while performing any desired series of calisthenic exercises, an electric generator in one of said dumb-bells or similar articles, which can be operated by the user while exercising, and electric connections from the poles of that generator to the hands of the user grasping the dumb-bells so that the current generated may include the arms and body of the user as a part of its circuit.

The best form of apparatus at present known to me embodying my invention is illustrated in the accompanying two sheets of drawings in which,

Fig. 1 is a perspective view of a pair of dumb-bells with the connecting electric wire broken away.

Fig. 2 is a face view of one end of that half of one of the dumb-bells carrying the electric current generating mechanism with the cover section removed to show the generator and part of the base plate broken away to show the ratchet driving mechanism, part of the insulating sheet also being broken away.

Fig. 3 is a similar view with the base plate removed to show the driving gearing carried on the rear side of said plate, the section being taken on line 3-3 of Fig. 4.

Fig. 4 is a partial section of the same end of the dumb-bell showing the said mechanism in side elevation, and

Fig. 5 is a diagram of the electrical circuits.

Throughout the drawings like reference characters indicate like parts.

1 represents a wooden dumb-bell, the lower end of which is made hollow and has a removable cover section 1^a forming the cavity 35 for containing an electrical generator and mechanism for operating the same. 2 is a similar wooden dumb-bell forming a pair with 1, but without the hollow end and removable cover therefor. 3 is a strip of conducting material carried by dumb-bell 1 in a position such that the hand of the user will rest upon it, which strip is in electrical contact with the base plate 14, carrying the generator mechanism, or with the sector lever 29, or with both. 4 is a similar strip on dumb-bell 2, having electrical connection to one end of wire 5, the other end of which is connected by wire 6 to the bifurcated brush 7 of the electric generator. 36 is a cut-out sheet of fibre or other electrically insulating material placed under cover section 1^a.

While various forms of electric generators may be used I have one which consists of a permanently magnetized field magnet 13, and armature core 11, provided with coils 12 wound thereon, said armature being carried by the revolving shaft 10 on which is the contact ring 8, insulated from the shaft by sleeve 8^a which is made of fibre or other non-conducting material. Said shaft also has radial metal projections 9 which are insulated from 8 by flange 8^b of fibre or similar material. One end 11^a of the armature coil 12 is connected to the generator shaft 10 as indicated in the diagram, Fig. 5, either directly or through the core 11, and the other end 12^a of said coils is connected to ring 8 as also shown in Fig. 5. The contact brush 7 has two branches 7^a and 7^b, the first of which rests continuously on the ring 8, and the second of which makes intermittent contact with the projections 9 from the shaft 10 when the armature is revolved.

The electrical operation of the device above described is obviously as follows: Assuming that a person holds the dumb-bell 1 in one hand and the dumb-bell 2 in the other hand with his hands in contact with the conducting strips 3 and 4 respectively, the circuit through his body, and the generator

will be as follows: From the hand resting on strip 4, through wire 5, through branch 7^a of the bifurcated brush 7, continuously resting on ring 8, through armature coil terminal 12^a, armature coils 12, connections 11^a to shaft 10 and from this shaft through base plate 14 or sector lever 29 and strip 3 to the other hand. If the armature of the generator is rotated, however, every time a projection 9 touches branch 7^b of the bifurcated brush 7 the armature coils are short circuited. The result then is that when the armature coils are so short circuited little or no current passes through the body of the user, but the moment the short circuit is broken by projection 9 breaking contact from brush section 7^b, the normal current being generated in the armature coils, plus the momentarily much more powerful current produced by the counter electromotive force released on the breaking of the short circuit, produce a decided shock in passing through the user's body.

Any convenient train of mechanism by which the thumb or a finger of the hand grasping dumb-bell 1 may drive the electric generator may be employed. In the form shown in the drawings there is a pinion 20 on armature shaft 10, meshing with gear 21 on stud shaft 22, said gear being rigidly connected to pinion 23 which meshes with gear 24 on ratchet stud shaft 25, said gear 24 carrying a spring pawl 27 which meshes with ratchet wheel 26. Ratchet wheel 26 rotates freely on stud shaft 25 and carries pinion 28 rigidly connected to it. This pinion 28 meshes with the teeth on pivot sector lever 29, pivoted to the base-plate 14 at 30, and having the loop or handle 31 at its other end which projects beyond the dumb-bell shell in a position to be conveniently grasped by the thumb or forefinger of the hand holding dumb-bell 1. Any convenient form of coil spring is shown at 32 tending to rotate sector lever 29 in a clockwise direction (looking at Fig. 3) so that the handle 31 will be retracted after the pressure of the thumb or finger thereon is relieved. 33, Fig. 3, is a cut-out space in lever 29 to permit it to straddle stud shaft 22, and 34 is similar cut-out space to enable it to straddle generator shaft 10.

In operation the user, holding the dumb-bells, places his thumb or forefinger in the loop 31 and intermittently pulls the outer end of lever 29 toward the axis of the dumb-bell, thereby rotating said lever on its axis 30 in a counter clockwise direction, (looking at Fig. 3), driving ratchet wheel 26 in a clockwise direction so that its motion is transmitted by pawl 27 to gear 24 and such motion, greatly increased in velocity, is subsequently transmitted by the train of gearing described to the generator shaft 10. 65 When pressure on loop 31 is released spring

32 rotates lever 29 and ratchet wheel 26 in the reverse directions, the ratchet wheel sliding under the pawl 27, and not interfering with the continued spinning of the generator armature. As a result continuous rotation of the generator armature at high speed can be ensured and the current thereby generated passed intermittently through the user's body as hereinbefore described.

Obviously other hand-operated driving mechanism for the generator could be substituted for that described and other forms of electric generator could be used without departing from the principle of my invention, so long as some form of electric current generator capable of being actuated by the user of the dumbbells, or their equivalents, is employed to generate a current which is transmitted through a circuit in which the body of the user is included during the use of the apparatus for exercising purposes.

The particular form of current generator and driving gear therefor herein shown and described has, however, certain novel features which particularly adapt it for use in the combination here claimed. Locating the generator on one side of base plate 14 and the driving gear on the other side thereof (as best shown in Fig. 4) enables me to divide the cavity necessarily formed in the dumb-bell into two parts, one in each of the two sections 1, and 1^a thereof, and so keep the size of the dumb-bell down to standard dimensions. This also enables me to locate sector lever 29 close to the medial plane of the dumb-bell so that the handle 31 is in a convenient position to be reached by the operator's thumb.

Also the formation of the grooved contact ring 8 with the flange 8^b of insulating material separating it from projections 9 which form the other terminal of the generator circuit, prevents either of the contact brush branches 7^a or 7^b from so twisting under changes of temperature or from loosened fastenings as to permanently short circuit the generator, or permanently open its circuit.

Having described my invention, I claim:

1. In an electric dumb-bell having an internal cavity in one end portion divided by a substantially central plane separating that end portion into two sections, the combination, with said dumb-bell, of an electric generator, a ratchet driving gearing therefor and a common bed plate for the two, adapted to be clamped between said dumb-bell sections, said generator being mounted on one side of said plate, said gearing being mounted on the other side, and the armature shaft of the generator extending through said plate to said gearing.

2. In a device of the kind described having an alternating current electric generator, the combination in said generator, of an

armature coil, an armature shaft connected to one end of said coil, contact projections from said shaft, a grooved contact ring mounted on, but insulated from, said shaft, and connected to the other end of said armature coil, a flange of insulating material separating said ring from said shaft pro-

jections, and a pair of contact fingers, one of which bears on the grooved portion of said ring and the other of which is adapted to make intermittent contact with said shaft projections.

VICTOR SENCE.
